UNITED STATES PATENT OFFICE.

ERNST F. W. WIEDA, OF PATERSON, NEW JERSEY.

CANDY-PACKAGING MACHINE.

SPECIFICATION forming part of Letters Patent No. 768,104, dated August 23, 1904.

Application filed December 23, 1903. Serial No. 186,355. (No model.)

To all whom it may concern:

- Be it known that I, ERNST F. W. WIEDA, a citizen of the United States, residing in Paterson, in the county of Passaic and State of New Jersey, have invented certain new and useful Improvements in Candy-Packaging Machines; and I do hereby declare the following to be a full, clear, and exact description of the invention, such as will enable others skilled in the art to which it appertains to make and use the same, reference being had to the accompanying drawings, and to characters of reference marked thereon, which form a part of this specification.
- This invention has for its object to provide a machine for use in packaging candies and other similar articles so as not only to expedite the packaging and reduce the cost of labor, but, which I view as of more importance, to eliminate the necessity of handling the goods. In the case of certain classes of candies, &c., particularly such as chocolate or cream coated ones, the least handling very materially deteriorates them by destroying that gloss and appearance of freshness which makes them attractive to the customer.
- The present invention is an improvement on that set forth in my United States application Serial No. 131,430.
- In the accompanying drawings, Figure 1 is a view in side elevation of a machine designed to accomplish the aforementioned objects. Fig. 2 is a top plan view of the right-hand end portion of the machine as seen in Fig. 1. Fig. 3 is an enlarged fragmentary side view involving that portion of the machine where the candies are dislodged from the sheets of paper on which they enter the machine and transferred to their permanent packing-sheets, a portion of the structure presented being in section. Fig. 4 is a view in side elevation of the right-hand end of the machine in a case where means is provided for automatically packing the candies mounted on their permanent packing-sheets in the boxes in which they are packaged, and Fig. 5 is a top plan view of what is seen in Fig. 4.
- After the final step in the process of making candies and the like they are usually laid in series of rows on sheets of paper until they
- harden sufficiently. They are afterward individually taken from the sheets and packed by hand in a box, being disposed according to the preferred way in tiers, each tier being supported by a sheet of cardboard or the like.
- My machine is designed to do the work of removing the candies or other articles from the sheets of paper on which they are placed to harden, then disposing them on the sheets of cardboard which support them in the box in which they are finally packed, and then (according to the modification shown in Figs. 4 and 5) successively laying such sheets thus laden with the candies in the proper disposition in said box. To this end the sheets of paper on which the candies are placed to harden and which are indicated at *a* in Figs. 1, 2, and 3 are laid on an endless apron *b*, which extends around a roller *c* and the edge remote from said roller of a table *d*, said roller being mounted in bearings *e*, made adjustable to and from the table *d* by the means *f* illustrated in Fig. 1, and the table *d* being, if so desired, a part of the structure of the frame *g* of the machine.
- In a bracket *h*, projecting from one side of the frame *g* and in said frame, is journaled the main or drive shaft *i*, which is rotated from a pulley *j*, which it carries and on which is fixed a bevel-pinion *k*, meshing with a pinion *l* on a shaft *m*, journaled in bearings *n* and extending toward the shaft or trunnion *o* of the roller *c*, with which shaft or trunnion the shaft *n* is intergeared, as by bevel-gearing *p*.
- The upper stretch of the apron *b* rests on the table *d*, so as thereby to obviate its sagging.
- At the edge *q* of the table *d* the papers must be deflected downwardly with the apron and in the present instance are designed to be piled on a support *r*, mounted in the frame *g*, to be used over again.
- In order to guide the papers around the edge *q*, I provide endless wires, cords, or other flexible connections *s*, which extend around pairs of pulleys *t*, supported in the frame. One pair of these pulleys is disposed somewhat in advance of the edge *q* of the table *d*.

and relatively close to the same, and these pulleys are engaged on their under sides by the wires, so that from these pulleys to the edge *q* of the table the wires stand close to the 5 papers, and so tend to guide them true. Two other pairs of these pulleys *t* are disposed close to the support *r*, the one above the other, the wires passing around the upper pair between them and the support and then around 10 the lower pair on the side which is the farther from the support, this arrangement of the two last-mentioned pairs of pulleys being designed to bring the wires close up to the support *r*, so that after the papers have been deflected around the edge *q* of the table *d* they 15 will be carried by the wires rearwardly and piled on the support *r*. The wires are caused to advance in the same direction as the apron *b* moves through the medium of a shaft *u*, 20 which is connected at one end by bevel-gearing *v w* with the shaft *m* and at the other end by bevel-gearing *x y* with a shaft *z*, carrying the upper one of the two pairs of pulleys *t* adjacent the support *r*. 25 1 designates another table arranged in horizontal alignment with the table *d* and having its edge 2 brought close up to the edge *q* of the table *d*. The edge portion referred to of the table 1 may be relatively thickened up 30 and well rounded, as at 3, so that the stiff paper or cardboard hereinafter referred to will stand close to its surface and not be broken.

Around the edge 2 of the table 1 and around rollers 4 and 5 extend spaced belts 6, provided 35 with spurs 7 equidistantly spaced. These belts are held under tension and are driven by the roller 5, whose shaft 8 carries at one end a bevel-gear 9 in mesh with a bevel-pinion 10 on a shaft 11, journaled in the bracket 40 *h* and a bracket 12, and carrying another bevel-pinion 13, meshing with the pinion *k*.

In a stand 14 is journaled a beam 15, carrying a roll 16, of cardboard or any other form 45 of paper or the like, preferably stiffened. For a purpose which will hereinafter appear this roll of paper is somewhat wider than the rows of candies are when finally discharged from the machine, and at regular intervals, corresponding in length to the number of rows of candies 50 which make up one unit in the box in which the candies are packaged, transverse slits 17 are formed. These slits of course do not extend entirely across the sheet, but leave intact a marginal portion 18, whose width may depend 55 on the strength and thickness of the paper, all as hereinafter indicated. The marginal portion 18 may be provided with orifices 19, with which the spurs 7 on the belts 6 are adapted to register, and thus cause the advance with 60 them of the sheet fed from the roll 16. If the spurs 7 are sharp enough, these orifices may be dispensed with, the spurs being depended upon to puncture the sheet, and so get a sufficient grip thereon to cause its advance.

65 At 20 is an inverted grid consisting of a

plate provided on its under side with convergent ribs or guides 21, the grid being supported by the frame *g* at such a distance above the same that the candies will clear the plate portion thereof in passing under it. Some or 70 all of the ribs 21 may be provided with fingers 22, which project down into the space between the edges *q* and 2 of the table and act to guide the strip of cardboard from roll 16 around the edge 2.

In brackets 23 is journaled a shaft 24, on which are mounted two rotary knives 25, spaced a distance corresponding to the length of each slit 17 in the strip of cardboard. The shaft 24 is rotated from the shaft *i* by a belt 80 26, passing over pulleys 27 and 28 on said shafts.

The operation of the machine as so far described is as follows: The sheets of paper or the like bearing the candies being successively 85 deposited on the apron *b*, the latter carries them toward the edge *q* of the table *d*. At this point the papers being deflected downwardly with the belt and then piled on the support *r* the candies are taken up by the strip of cardboard 90 from the roll 16, which is caused to advance by the belts 6. As the candies advance with the belt they enter between the ribs or walls 21 of the grids 20 and by virtue of their convergence are crowded together, as illustrated 95 in Fig. 2, into a space which is not wider than the distance between the marginal portions 100 of the strip of cardboard. Meanwhile the rotary knife is operating to cut the marginal portions of the strip away from the body portion thereof—that is to say, the portion which is slit transversely—with the result that the strip of cardboard is converted 105 into separated sections or sheets bearing the candies and marginal strips. The marginal strips may be deposited in receptacles 110 29 to be used for other purposes or discarded. The package units thus produced and each consisting of a separate sheet of cardboard or the like bearing a group of candies, may be 115 either taken by hand from the table 1 and placed in their boxes or without being deposited on said table after the cutting out of the sections or sheets of cardboard they may be automatically packed in their containers, 120 as is illustrated in Figs. 4 and 5. In this instance the table 1 extends only approximately as far as the end of the frame *g*. The frame *g* carries a bracket 30, in which is adjustably secured by thumb-screws 31 the legs 32 of a 125 support 33. This support has an opening 34 therein to accommodate a plunger 35, having handles 36 and teeth 37. In a bracket 38 is a pawl 39, normally pressed into engagement with the toothed portion of the plunger by a 130 spring 40 and adapted to be drawn out of engagement with the plunger by a mechanism comprising a bell-crank lever 41, having one end pivoted to the free end of the pawl, a pitman 42, having one end pivoted to the 135

other end of the bell-crank lever and pressed downwardly by a spring 43, and a bell-crank lever 44, having one end connected to the other end of the pitman and its other end projecting in the path of lugs 45, carried by one of the belts 6. 46 is a skeleton box, of cardboard or the like, having an opening 47 in the bottom thereof to accommodate the plunger, and 48 is the box proper, in which the candies 5 are immediately packed, the same having the side adjacent the table 1 removed and being directly carried by the plunger. In the operation of this mechanism as the lugs 45 approach and actuate the bell-crank lever 44— 10 in other words, as fast as the sections of cardboard bearing the candies are cut out from the strip of cardboard—the pawl 39 is drawn inwardly, to be thereupon immediately released by the lug having passed the lever 44, so that 15 the result is that the plunger 35 drops only one tooth each time the pawl is drawn back.

In order to protect the tops of the candies from being damaged by the supporting-sheet of the next incoming tier or group of candies, an attendant may place a sheet of cardboard or paper over each tier of candies as it 20 is delivered into the box.

As shown in the drawings, the grid 20 is designed to be removable, so as to change it 25 for another grid having its guides arranged at a different distance from each other.

Having thus fully described my invention, what I claim as new, and desire to secure by Letters Patent, is—

30 1. In a machine for packaging candies or other similar articles, the combination of the frame, means for advancing the articles in substantially horizontal disposition, a sheet-like support disposed in approximately horizontal alignment with the plane of advance of said articles, and means for advancing said support, substantially as described.

2. In a machine for packaging candies or other similar articles on a portable supporting sheet or sheets, the combination of the frame, an endless traveling belt having its upper stretch approximately horizontal and carrying said sheet or sheets, said belt having spurs adapted to penetrate and thus grip said 45 sheet or sheets, and means for depositing said articles on said sheet or sheets, substantially as described.

3. In a machine for packaging candies or other similar articles, the combination of the frame, two endless flexible carrying or advancing devices having their upper stretches substantially horizontal and the adjacent ends of said stretches close together, and means for advancing said flexible devices in the same 55 direction, substantially as described.

4. In a machine for packaging candies or other similar articles, the combination of the frame, two endless flexible carrying or advanc-

ing devices having their upper stretches substantially horizontal and the adjacent ends of 65 said stretches close together, means for advancing said flexible devices in the same direction, and a grid arranged above one of said devices and having convergent guides extending in the direction of advance of said devices, substantially as described.

5. In a machine for packaging candies or other similar articles, the combination of the frame, means for advancing a sheet-like support for said articles, means for depositing 75 the articles on said support, and means for effecting the separation of said support into permanent divisions each sustaining a group of said articles, substantially as described.

6. In a machine for packaging candies or other similar articles, the combination of the frame, means for advancing a sheet-like support for said articles having incisions extending part way across the same, means for depositing the articles on said support, and 85 means for effecting the separation of said support at said incisions into permanent divisions each sustaining a group of said articles, substantially as described.

7. In a machine for packaging candies or 90 other similar articles, the combination of the frame, means for advancing a sheet-like support for said articles having incisions each of which extends from one to the other marginal portion of said support, means for depositing 95 the articles on said support, and means for detaching the marginal portions of said support along a line approximately coincident with the ends of said incisions, substantially as described.

8. In a machine for packaging candies or other similar articles, the combination of the frame, means for advancing a sheet-like support for said articles having incisions each of which extends from one to the other marginal portion of said support, and means for cutting 105 said support along a line longitudinal of said marginal portions and approximately coincident with the ends of said incisions, substantially as described.

9. In a machine for packaging candies or the like, the combination of an approximately horizontal movable support adapted to advance the articles in the machine, and convergent walls disposed above said support 115 with their discharge ends the closer together so as to bring said articles into close disposition during the advance of said support, substantially as described.

In testimony that I claim the foregoing I 120 have hereunto set my hand this 21st day of December, 1903.

ERNST F. W. WIEDA.
